(57) **CLAIM**

The ornamental design for a pulse oximetry sensor, as shown and described.

DESCRIPTION

FIG. 1 is a top, front and side perspective view of a first embodiment of a pulse oximetry sensor embodying my new design.

FIG. 2 is a bottom, back and side perspective view thereof.

FIG. 3 is a back and side view thereof.

FIG. 4 is a front and side view thereof.

FIG. 5 is a front view thereof.

FIG. 6 is a back view thereof.

FIG. 7 is a first side view thereof.

FIG. 8 is a second side view thereof.

FIG. 9 is a top view thereof.

FIG. 10 is bottom view thereof.

FIG. 11 is a cross-sectional view taken along line 11-11 of FIG. 9.

FIG. 12 is a cross-sectional view taken along line 12-12 of FIG. 9.

FIG. 13 is a cross-sectional view taken along line 13-13 of FIG. 9.

FIG. 14 is a top, front and side perspective view of a second embodiment of a pulse oximetry sensor embodying my new design.

FIG. 15 is a bottom, back and side perspective view thereof.

FIG. 16 is a back and side view thereof.

FIG. 17 is a front and side view thereof.

FIG. 18 is a front view thereof.

FIG. 19 is a back view thereof.

FIG. 20 is a first side view thereof.

FIG. 21 is a second side view thereof.

FIG. 22 is a top view thereof; and,

FIG. 23 is bottom view thereof.

Broken lines are used to illustrate features of the pulse oximetry sensor which form no part of the claimed design. The cross-sectional views of FIGS. 11-13 form no part of the claim design but illustrate certain of the contours of the pulse oximetry sensor.
